CLAIM

I claim the ornamental design for a vehicle headlight, as shown and described.

DESCRIPTION

FIG. 1 is a right, front perspective view of a first embodiment of a vehicle headlight showing my new design, FIG. 2 is a front view thereof, FIG. 3 is a left side view thereof, and FIG. 4 is a top view thereof.

FIG. 5 is a left, front perspective view of a second embodiment of a vehicle headlight showing my new design, FIG. 6 is a front view thereof,

FIG. 7 is a right side view thereof; and,

FIG. 8 is a top view thereof.

The broken lines depict environmental subject matter, are for illustration only, and form no part of the claimed design.

1 Claim, 4 Drawing Sheets
